UNITED STATES PATENT OFFICE.

ABRAHAM LINCOLN HOLTZMAN, OF EAST ORANGE, NEW JERSEY.

BRUSH.

1,077,071.

Specification of Letters Patent. Patented Oct. 28, 1913.

Application filed December 12, 1912. Serial No. 736,280.

To all whom it may concern:

Be it known that I, ABRAHAM LINCOLN HOLTZMAN, a citizen of the United States, and a resident of East Orange, in the county of Essex and State of New Jersey, have invented a new and Improved Brush, of which the following is a full, clear, and exact description.

The invention relates to brushes such as shown and described in the Letters Patent of the United States, No. 1,045,552, granted to me on November 26, 1912.

The object of the present invention is to provide a new and improved brush arranged to permit the user to conveniently and quickly replace a worn out bristle holder by a new one and to allow thorough cleaning of the bristle holder and the support thereof with a view to keep the brush at all times in sanitary condition.

In order to accomplish the desired result use is made of a handle having an integral head provided with a recess and with a rabbet, the said head being also provided at the forward end with an integral flange, a bristle-holding plate seated on the said rabbet and having its forward end seating on the said flange, the rear end of the said plate terminating in a tongue and a ring held on the neck of the said head and adapted to engage the said tongue and clamp the same against the neck.

A practical embodiment of the invention is represented in the accompanying drawings forming a part of this specification, in which similar characters of reference indicate corresponding parts in all the views.

Figure 1 is a perspective view of the brush in the form of a tooth brush; Fig. 2 is a longitudinal section of the same; Fig. 3 is an enlarged cross section of the same on the line 3—3 of Fig. 2; and Fig. 4 is a perspective view of the removable bristle holder.

In my patent above referred to the bristle holder is inserted into an open loop from the top thereof, and a separate covering and locking plate is used to close the top of the loop and lock the bristle holder in place in the loop. In my present invention the covering and locking plate is entirely dispensed with and the bristle-holding plate carrying the bristles or other brush stock forms the covering plate and is removably locked in

position on the handled head of the brush. 55 In the tooth brush shown in the drawings, the handle A is provided at its forward end with a head B having a recess therein to receive the bristle-holding plate C, the said head B being also provided with a rabbet B' 60 against which the sides of the bristle-holding plate C rest when in place. The outer end of the head B is provided with a flange E to support the outer end of the bristle-holding plate C. The rear end of the bristle-holding plate C is in the form of a tongue C² resting on the under side of the head B at the neck B² thereof, and which neck joins the handle A. The tongue C² is 65 adapted to be engaged by a ring F, slidably held on the neck B² to clamp the tongue C² in position on the neck B² of the head B. In order to hold the ring F against accidental displacement on the neck B² and the tongue C², the latter is provided with a recess C³ adapted to be engaged by said ring F so as to securely clamp the tongue in position. On sliding the ring F rearwardly it 70 disengages the tongue C², thus unlocking the latter and allowing the user to remove the bristle holder from the head B whenever it is desired to replace the worn out bristle holder by a new one or to permit of 75 disassembling the parts to allow of cleaning the same with a view to keep the brush at all times in sanitary condition. The flange E forms an integral part of the outer end of the head B, and is preferably half round, and the outer end C' of the bristle-holding plate C is correspondingly shaped, 80 so that the said end snugly fits onto the flange and is supported thereby, and when the ring F is slipped over the tongue C², the bristle-holding plate is securely fastened 85 in position on the head. 95

The brush shown and described is very simple in construction and composed of comparatively few parts, which can be readily assembled and disassembled for the purposes mentioned.

Having thus described my invention, I claim as new and desire to secure by Letters Patent:

A brush, comprising a handle having an integral head provided with a recess and with a rabbet, the said head being also provided at the forward end with an integral flange, a bristle-holding plate seated on the

said rabbet and having its forward end resting on the said flange, the rear end of the said plate terminating in a tongue, and a ring held on the neck of the said head and adapted to engage the said tongue and clamp the same against the neck.

In testimony whereof I have signed my

name to this specification in the presence of two subscribing witnesses.

ABRAHAM LINCOLN HOLTZMAN.
